UNITED STATES PATENT OFFICE.

ALEXANDER DOW, OF NEW YORK, N. Y.

CASE-HANDLING DEVICE FOR TYPE-SETTING MACHINES.

No. 833,958.

Specification of Letters Patent.

Patented Oct. 23, 1906.

Application filed July 2, 1902. Renewed October 23, 1905. Serial No. 284,034.

To all whom it may concern:

Be it known that I, ALEXANDER DOW, a citizen of the United States of America, and a resident of Park Row Building, city and 5 State of New York, have invented certain new and useful Improvements in Case-Handling Devices for Type-Setting Machines, of which the following is a specification.

My invention relates to a case-handling 10 device; and the object thereof is to produce a mechanism whereby a case containing type or matrices may be handled more conveniently and quickly than heretofore.

My invention is especially adapted to use 15 in connection with composing-machines.

In composing-machines, whether they use 20 type or matrices, in which it is possible to use various sizes in the same machine it is more convenient to be able to remove the cases 25 containing these type or matrices and place new cases in position than it is to take the type or matrices out of all the channels of the cases and replace them with those of different size.

25 My invention specifically relates to a means whereby the cases can be easily placed in position in the machine and whereby when it is desired to remove the cases they can be moved to a position from which 30 they can be easily lifted off and carried away.

With this and other objects in view the invention consists of certain parts and combinations, the preferred form of which will be first specifically described and then the 35 invention pointed out in the claims.

Referring to the drawings, wherein like reference-numerals are used to indicate the same part wherever it occurs, Figure 1 is a front elevation of the preferred form of my 40 case-handling mechanism, one of the cases being removed to more plainly show the construction. Fig. 2 is a sectional view taken on the line 2 2 of Fig. 1. Fig. 3 is a rear view of the case-handling mechanism, both the 45 cases being shown in position, with some of the parts broken away to more clearly show the construction. Fig. 4 is a plan view of one of the cases. Fig. 5 is an end view, partly in section, the section being taken on 50 the line 5 5 of Fig. 4. Fig. 6 is a longitudinal section taken on the line 6 6 of Fig. 4. Fig. 7 is a detail view of one of the partitions of the case. Fig. 8 is a diagrammatic view showing the various positions the case occupies when 55 operated. Fig. 9 is a vertical longitudinal section of the case-handling mechanism and

case, taken on two vertical planes, one central to the handling mechanism on the line a a of Fig. 3 and one central of the case on the line b b of Fig. 3, some of the parts being 60 broken away for better illustration. Fig. 10 is a detail sectional view similar to Fig. 9, showing the mechanism in a different position from that which it occupies in Fig. 9. Fig. 11 is a vertical longitudinal sectional de- 65 tail of the case, taken on line 11 11 of Fig. 3.

Referring to Fig. 8, 1 indicates a composing-machine of any desired form. For the sake of illustration the composing-machine shown is the machine which forms the sub- 70 ject-matter of my application, Serial No. 114,153, filed July 2, 1902.

In the composing-machine shown in the application referred to the type are carried 75 in channels in the cases and are forced out from the bottom of these channels by a mechanism actuated by the operator upon the depression of the proper keys of a keyboard. The type are forced out in front of the channels and are carried away by a suitable mech- 80 anism to a channel, where they are assembled in a line.

In practice the lower ends of the cases stand normally within and are surrounded 85 by parts of the setting mechanism, and to remove the cases it is first necessary to lift them, then tilt the lower end of the cases forward outside of and clear of the parts of the setting mechanism, and afterward lower the cases, so that their lower ends are over the 90 front of the machine in a position where they are accessible.

By reversing the operation the cases are returned to their normal position.

Mounted on suitable bearings in the frame 95 2 of the machine is a shaft 3, and fast thereon are the pinions 4 4 and a worm-gear 5. The gear 5 meshes with the worm 6, mounted on a shaft 7, which is provided at its end with a crank 8, whereby the worm may be revolved. 100

Mounted on the shaft 3 by means of the boxes 10 10 is a frame 9. This frame is provided with suitable longitudinal grooves 11 11 in the form of undercuts, which together form a dovetailed guide for a second frame. 105

The sides of the frame 9 are connected together by cross-pieces 12 12, which strengthen and stiffen the frame. Sliding in the grooves 11 11 are the sides 13 13 of a second frame 14, the sides of this second frame being also suitably connected together by means of the cross-pieces 15 15. The frame 9 is also pro-

vided with a central longitudinal web 16, mounted upon the cross-pieces 12, and the frame 14 has a central longitudinal web 17, corresponding to the web 16 and sliding thereon. On the central web 17 the inner edges of the two cases rest when they are in position. Mounted on the back of each of the sides 13 13 of the frame 14 is a rack 18. These racks 18 18 mesh with the pinions 4 4 upon the shaft 3, whereby when the shaft 3 is rotated by the crank 8 through the worm-gear the frame 14 will be moved longitudinally of the frame 9.

19 represents the cases, which are formed in the shape of substantially rectangular boxes, and each case consists of a back 20, the side pieces 21, the upper end 22, and the lower end 23, these parts being suitably secured together by bolts, as shown. The back 20 does not extend the full length of the case; but between the lower end of the back and the lower end bar 23 a space is left of sufficient width to allow the type to be forced out from the lower end of the channels formed in the case by any suitable mechanism. The channels are formed in the case by dividing strips 24, one of which is shown in detail in Fig. 7. These strips run the length of the case and are supported at the ends in the bars 22 23 and divide the case into a series of channels of equal width.

25 represents type or matrices in position in the channels, and 26 represents followers placed on top of the lines of type in the channels to keep the same always at the bottom of their channels. Mounted on the sides of the case are handles 27, whereby the cases may be conveniently lifted off and carried about, as required. On the top edge of the sliding frame 14 are the lugs 28 28, which are engaged by the hooks 29 29, secured to the back of the cases. By means of these hooks the cases are attached to and caused to move with the sliding frame. Secured to the rear of the frame 9 is a handle 30, by means of which the frame can be tilted on the shaft 3 after the cases have been elevated in order to swing the lower ends of the cases clear of the composing mechanism. Mounted in suitable bearings near the lower end of the swinging frame 9 is a shaft 31, carrying a pair of hooks 32, each hook being provided with an angular point 36.

34 34 are brackets secured to the frame of the machine and projecting rearwardly below the hooks 32 32. On the front edge of each of the brackets is a stop 33 and below it a notch 38 of a size and shape to receive the angular point 36 of the hook 32. At the rear end of each of the brackets 34 is a set-screw 35, adapted to be set to limit the rearward motion of the lower end of the cases. The hooks ride on the brackets and are moved by the swinging of the frame, carrying 65 the cases from the position shown in Fig. 9

to the position shown in Fig. 10. When in the tilted position shown in Fig. 10, the angular ends 36 of the hooks 32 engage the notches 38, and the frame carrying the cases is locked in its position. 7c

37 is a hand-lever fastened to the shaft 31, by means of which the hooks may be raised to disengage their angular ends 36 from the notches 38 in the brackets to allow the frame carrying the cases to be swung back to its 75 normal position.

The operation of my device is as follows: When it is required to remove the cases which are in position in the machine, the crank 8 is turned, and through the worm-gear and rack connections the sliding frame 13, carrying the cases, is lifted up until the lower ends of the cases are clear of the composing mechanism, as shown in dotted lines in Fig. 8. Then by means of the handle 30 85 the case-carrying structure is tilted upon the shaft 3 until the hooks 32 engage the stops 33, when the angular ends of the hooks will drop into the notches 38 in the brackets and hold the carrying structure in its forward position. The crank 8 is then turned in the opposite direction, when the frame 13, carrying the type-cases, will be lowered into the position shown partly in dotted and partly in full lines in Fig. 8, and the cases will be in position to be accessible. 90 95

By merely reversing the above-described operation the cases may be returned to their normal positions in the machine.

Having thus described my invention, what I claim as new, and desire to secure by Letters Patent, is—

1. In a composing-machine the combination with a case, of means for supporting the case in operative relation to the composing mechanism, and means for lowering the case out of operative relation to the composing mechanism. 105

2. In a composing-machine the combination with a case, of means for supporting the case in operative relation to the composing mechanism, and means for raising the case and then lowering it out of operative relation to the composing mechanism. 110

3. In a composing-machine the combination with a case, of means for supporting the case in operative relation to the composing mechanism, and means for raising, tilting and lowering the case out of operative relation to the composing mechanism. 115

4. In a composing-machine the combination with a case, of means for pivotally supporting the case in operative relation to the composing mechanism, and means for raising the case, tilting it on its pivot and lowering it out of operative relation to the composing mechanism. 120 125

5. In a composing-machine the combination with a case-support pivoted on the machine and adapted to be swung on its pivot 130

to change the inclination of the case, a case-carrier mounted on the case-support, and means for moving the case-carrier up and down on the support so as to change its relation thereto.

6. In a composing-machine the combination with a case-support pivoted on the machine and adapted to be swung on its pivot to change the inclination of the case, of a case-carrier mounted on the case-support and provided with a rack, a gear suitably mounted and meshing with the rack, and means for turning the gear whereby the case-carrier will be moved up and down on the case-support so as to change its relation thereto.

7. In a composing-machine the combination with a case arranged substantially vertical, of means for elevating the case, means for moving the case so that it will clear the composing mechanism, and means for then lowering the case to bring the same in an accessible position.

8. In a composing-machine the combination with a case, of a frame supporting the case, and means for raising and lowering the frame to carry the case out of operative relation to the composing mechanism and then to a position below the composing mechanism.

9. In a composing-machine the combination with a pivoted frame, a second frame movable thereon, a case supported by the second frame, and means for moving the second frame in relation to the first frame, to permit the case to be swung with the first and second frames so as to clear the composing mechanism and then lowered.

10. In a composing-machine the combination with a pivoted frame, a second frame movable thereon, means for moving the second frame in relation to the first frame, whereby the second frame may be raised and

swung so as to clear the composing mechanism and then lowered.

11. In a composing-machine the combination with a pivoted frame, a second frame movable thereon, a case supported on the second frame, means for moving the second frame in relation to the first frame, whereby the second frame carrying the case may be raised and swung out of operative relation to the composing mechanism and then lowered.

12. In a composing-machine the combination with a shaft of a frame mounted thereon and adapted to swing about the shaft, a second frame movable in ways on the first-mentioned frame, a rack on the second frame, a gear on the shaft meshing with the rack, means to actuate the gear, and a case secured to the second frame, whereby the case carried by the second frame may be placed in position in the machine and also lowered into accessible position.

13. In a composing-machine the combination with a shaft, a frame mounted thereon and adapted to swing about the shaft, a second frame movable in ways on the first-mentioned frame, a rack on the second frame, a gear on the shaft meshing with the rack and means to actuate the gear, a case secured to the second frame, and a catch for limiting the swinging movement of the first-mentioned frame on the shaft.

14. In a composing-machine the combination with a case, of means for pivotally supporting the case whereby it may clear the composing mechanism, means for limiting the swing of the case and means for lowering the case below its normal position.

Signed by me at Baltimore city and State of Maryland this 6th day of June, 1902.

ALEXANDER DOW.
